DAVID S. GILBERT, OF READING, PENNSYLVANIA.

QUICK-ACTION TRIPLE VALVE.

942,634.

Specification of Letters Patent. Patented Dec. 7, 1909.

Application filed August 11, 1909. Serial No. 512,393.

To all whom it may concern:

Be it known that I, DAVID S. GILBERT, a citizen of the United States, residing in the city of Reading, county of Berks, and State 5 of Pennsylvania, have invented certain new and useful Improvements in Quick-Action Triple Valves, of which the following is a specification.

This invention relates to quick-action 10 triple valves for air-brakes, wherein are provided means for effecting the sudden stoppage of a train in cases of emergency, by the direct admission of train pipe pressure to the brake cylinder, and the immediate 15 reinforcement of said pressure by the pressure from the auxiliary reservoir; and wherein is provided to coöperate with said means, a pressure-reducing valve or blow-down device, to reduce the high-speed pressure, proportionately to the reduction in the 20 speed of the train, to a predetermined maximum degree.

The chief object of my invention is to supply a quick-action device of this character 25 which will place the train pipe automatically in communication with the brake cylinder and at the same time confine, and direct the application of, the pressure from the auxiliary reservoir, and which will consist of few parts, all of which are comparatively simple in construction and capable of being manufactured at considerably less cost than the apparatus now in general use for accomplishing this purpose.

35 A further object of my invention is to furnish a new and novel form of pressure-reducing valve or blow-down device, which is very efficient in action and is adapted to be directly attached to the casing of the 40 triple valve.

With the above and other objects in view, the invention consists in the novel construction and arrangement of parts, as herein fully described, illustrated and claimed.

45 In the drawings, Figure 1 is a longitudinal sectional view showing a system of valves embodying my invention. Fig. 2 is a fragmentary view on an enlarged scale and partly in section of the emergency valve 50 controlling the entrance of the air passage leading from the train pipe chamber to the brake cylinder. Fig. 3 is a view similar to Fig. 1 showing the valve in position for an emergency stop. Fig. 4 is a view on an 55 enlarged scale, partly in section, of the check valve located in the air passage forming the

communication between the train pipe and the brake cylinder. Fig. 5 is a sectional view on an enlarged scale of a portion of the valve shown in Fig. 3, showing a modified form of valve seat. Fig. 6 is an enlarged longitudinal sectional view of the pressure-reducing valve; Fig. 7, a horizontal sectional view of a portion thereof on the line α γ Fig. 8; and Fig. 8, a fragmentary 60 65 elevational view of a portion of the bushing occupying the upper portion of the pressure-reducing valve.

Similar characters of reference refer to similar parts throughout the several views.

The present embodiment of my invention consists, as shown in the drawings, of three main parts, 1, 9 and 14, all of which are flanged and tightly bolted together. Part 1 is formed with an inlet to which a train 75 pipe of the usual construction may be detachably secured by means of the connection 21, and this part contains the usual drip chamber 22 communicating through a comparatively constricted passage with a chamber 23 in the upper part thereof. Part 9 80 comprises a single casing, in the upper portion whereof is contained the mechanism of the triple valve now in common use, comprising the valve piston 7 movable in the cylinder 25, and rearwardly thereof, the slide valve 8 movable in the chamber 29, which chamber communicates at its rear end with the auxiliary reservoir, which it has not been deemed necessary to illustrate.

Openings 24 in a partition α between the chamber 23 and the cylinder 25, together with the usual by-pass port in the cylinder bushing and the grooves in the rear face of the valve piston, establish communication 95 through chamber 29 from the train pipe to the auxiliary reservoir. Slide valve 8, which is engaged by the stem of the valve piston in the usual way and actuated by the same, contains the usual pin or graduating valve 100

b , the port c controlled thereby which is adapted upon ordinary service applications of the brakes to register with port 31 formed in the lower wall of the chamber 29, the passage d forming communication between port 31 and exhaust port 32, and the L-shaped port 30 opening into chamber 29 in the rear end of the valve, which latter port comes into play only upon emergency applications of the brakes in the manner as 110 will be hereinafter described.

With the exception of the port last men-

tioned, the parts and construction of the apparatus thus far described are so well known by all persons familiar with the art as to require no further explanation of their 5 several functions and modes of operation.

Referring now to the parts of the apparatus more immediately comprising my invention, 26 indicates a passage leading from chamber 23 to chamber 27 in the lower portion of part 9 immediately below the slide valve chamber 29. Said passage is preferably and most conveniently located, partly in partition *a* between chamber 23 and cylinder 25, and partly below the cylinder 25 10 in part 9. At its upper entrance this passage is controlled by the emergency valve 4 having a stem extending into a socket on the inner side of the cap nut 2. Attached to this valve and preferably secured thereto 15 by means of a nut immediately behind the head thereof, is a yoke-like stop having two fingers arranged substantially parallel with the valve stem and projecting through two openings 24, on either side of the passage 26, 20 into the cylinder 25. The intermediate portion of the yoke is provided, as shown in Figs. 2 and 5, with an opening, whereby it may be slipped over the valve stem and thus 25 rigidly secured by the nut. Openings 24, 30 being somewhat larger than the fingers of the yoke, act as guides therefor, while at the same time permitting the passage of air from the chamber 23 to the cylinder 25. A coil spring 3 encircles the stem of the 35 valve, abutting against the cap nut at one end and against the stop-holding nut at the other, and the tension of this spring is such that it will resist the forward movement of the valve piston when the latter is forced 40 against the stop fingers in an ordinary service application of the brakes, but will yield and allow the valve to be unseated and the 45 passage 26 to be opened for the passage of air from the train pipe when the valve piston acts under the conditions of an emergency application.

In Fig. 5 is shown a modification of the entrance to the passage 26, in which a bushing, of bronze, brass, or other suitable material, is supplied to form the seat against which the valve normally rests. Chamber 27, in the lower portion of part 9, is in communication with chamber 29 through port 31, and the same also communicates with 50 passage 26, but is normally closed to the same by the check valve 10 seated in the bushing 11 in the partition defining the forward end of the chamber. The stem of this valve is supported and guided in a central tubular extension (see Fig. 4) of a skeleton plug 13 threaded into the opposite end of the chamber and containing openings 28 through which communication is established 55 with the brake cylinder. A shoulder *e* formed on the valve stem limits the inward

movement of the valve by impingement against the end of the tubular extension, and a coil spring 12 encircling the stem and abutting at one end against the head of the valve and at the other against an annular shoulder 7c formed on the tubular extension, retains the valve normally upon its seat with just sufficient force to prevent leakage into the passage 26.

The pressure-reducing valve which I provide in connection with my invention for blowing down the high pressure in the brake cylinder upon an emergency application of the brakes, thereby preventing the locking of the train wheels and consequent sliding 75 on the rails, is comprised in what I have shown in the drawings and designated as part 14, which consists of a casing having a flange at its upper end whereby it is securely bolted to part 9 below the chamber 27. An 80 opening 33 in the lower wall of chamber 27 communicates with the upper end of the main chamber 34 of this valve through perforations 44 in the top of the bushing 20 occupying the upper interior portion of the 85 casing. Adapted to have limited reciprocation in the chamber 34 and to contact circumferentially with the cylindrical wall of the bushing, is arranged a piston 18, having an upper guided stem 18^a and a lower stem 18^b. A gasket 43, held in place by a nut 40 and a washer 41, covers the upper face of the piston, and impinges against an inwardly-projecting shoulder 42 forming an annular seat for the piston adjacent the upper end of the bushing. Normally, and so long as the pressure exerted upon the piston does not exceed that of service applications, the same is held firmly against this seat by the tension of the adjustable spring 17, which acts 90 thereon through the spring cap 19 abutting against the lower stem 18^b. Spring 17 abuts at its lower end against the bottom of the chambered nut 16, whereby it may be regulated to exert any desired amount of force 95 on the piston, and the pocket lock-nut 15 is provided to jam against the lower end of the valve casing and thus retain the parts in adjusted position.

Immediately below the shoulder 42, bushing 20 is provided with a series of small circular vents or perforations 46 (see Figs. 7 and 8), spaced apart and arranged in a true annular line. These vents open inwardly into the chamber 34, and communicate outwardly with a passage 45 in the casing, formed by a circumferential groove cut in the outer face of the bushing, which latter communicates in turn, through a similarly formed longitudinal passage grooved in the 115 bushing, with a longitudinal radial elongated slot or opening 48 which opens into the chamber 34 below the vents and below the piston 18 when the latter is normally positioned upon its seat. In the preferred 120 125 130

form of my invention I employ only one slot 48, but it is obvious that two or more slots with corresponding connecting passages such as 47, may be used without departing from the spirit of my invention. Upon the piston being depressed, air gaining the upper part of the chamber 34 from the brake cylinder, will be enabled to pass through the vents and passages described and in this manner reach the portion of the chamber below the piston, whence it is exhausted into the atmosphere through the openings 49 in the spring cap 19, the central opening 36 in the nut 16, and the opening 38 in the bottom 15 of the pocket nut 15.

Having thus described the parts and assemblage of the apparatus, its operation may be traced as follows: Assuming the valve to be in release position as shown in Fig. 1, air from the train pipe enters the drip chamber 21, and thence passes through chamber 23, openings 24, cylinder 25, by-pass port and piston grooves and valve chamber 29, to the auxiliary reservoir, charging the same. When now the pressure in the train pipe is reduced by the engineer to the extent necessary to produce an ordinary service application of the brakes, the valve piston 7 will be thrust forward by the pressure of the auxiliary reservoir until it contacts with the fingers of the stop 6, when its further forward progress will be arrested by the tension of the spring 3, which latter at the same time acts to keep emergency valve 4 tightly upon its seat. In this position of the valve, service port *c* in the slide valve 8 will register with port 31, permitting the pressure in the chamber 29 to be communicated through said ports into the chamber 27 and thence to the brake cylinder. Adjustable spring 17 in the pressure-reducing valve being set so as to resist a predetermined maximum degree of pressure which in every case equals, and may if desired, exceed that of the auxiliary reservoir when acting by itself, it is obvious that said valve will not be actuated or brought into play, and that the air in the brake cylinder must, upon return of the slide valve to its normal position, exhaust into the atmosphere through port 31, passage *d* and vent 32. When, however, it is desired to bring a train running at a high rate of speed to a sudden stop, the engineer's brake valve is thrown to emergency. This causes the pressure in the train pipe to be reduced considerably below the degree of service applications, rendering the pressure in the auxiliary reservoir so far superior to that acting on the front face of the valve piston as to thrust the piston forward, overcoming the resistance of the spring 3 and unseating the valve 4. Train pipe pressure now rushes into the passage 26, unseats check valve 10, and passes through chamber 26

into the brake cylinder. Also, the slide valve 8 being now in its extreme forward position, L shaped port 30 registers with port 31, and auxiliary reservoir pressure enters the brake cylinder through chamber 27 to supplement and reinforce the train pipe pressure already acting on the brakes. This high pressure now closes the valve 10 and thus confines the air to the brake cylinder.

At the same time, the tension of the spring 17 of the pressure-reducing valve is overcome by the force of the high pressure acting upon the piston 18 and the piston is depressed into the chamber 34, opening vents 46 and to a great extent overlapping and closing the slot 48. A small portion of the confined air now escapes, finding its way through the vents 46, the passages 45 and 47 and the slightly uncovered portion of the slot 48, to the lower part of the chamber 34, and thence by openings 49, 36 and 38 to the atmosphere. It is evident that as the air is thus permitted slowly to escape, the pressure in the brake cylinder and hence also upon the piston 18, will slowly and proportionately decrease, and that the piston will be gradually returned to its seat through the action of the spring 17. The return of the piston proceeds very tardily at the initial stage of this action owing to the fact that the construction is such as to allow only a very constricted portion of the slot 48 to remain uncovered, but as the piston gradually ascends to its normal position, the slot becomes more and more uncovered and a constantly increasing quantity of air is allowed to escape, and this process goes on until the piston regains its seat and closes the vents, when, as is evident, the pressure in the brake cylinder will again be reduced to the degree previously determined by the adjustment of the spring. It is clear that this gradual increase in the volume of the outflowing air, may, by properly proportioning the vents 46 and the slot 48, be made to proceed simultaneously with, and in substantial proportion to, the gradual reduction in the speed of the train.

Having thus described my invention what I claim as new and desire to secure by Letters Patent, is—

1. In a quick-action triple valve, the combination, substantially as set forth, of a triple valve proper, an emergency valve located in a chamber immediately forward of the piston cylinder of the triple valve, a yoke-like stop secured to said valve having two fingers extending into the cylinder of the triple valve through openings in the partition between said chamber and said cylinder, a spring acting to close said valve and restrain the movement of the triple valve piston, a check valve in said emergency air passage, and a pressure-reducing valve adjacent said check valve for blowing down

the pressure in the brake cylinder in emergency applications of the brakes.

2. In a quick-action triple valve, the combination, substantially as set forth, of a triple valve proper, an emergency valve located in a chamber immediately forward of the piston cylinder of the triple valve and having movement in line with the direction of movement of the triple valve, a yoke-like stop secured to said valve having fingers extending into the cylinder of the triple valve through air passages in the partition between said chamber and said cylinder, an emergency air passage leading to the brake cylinder having an entrance between said fingers and controlled by said valve, a spring encircling the stem of said valve acting to normally close the same and limit the movement of the triple valve piston in ordinary service applications and to yield to the pressure of said piston and open said valve in emergency applications, a check valve in said emergency air passage, and a pressure-reducing valve adjacent said check valve.
3. In a quick-action triple valve, the combination substantially as set forth, of a triple valve proper, an emergency valve located in a chamber adjacent the piston cylinder of the triple valve and having movement in line with the direction of movement of the triple valve, a partition between said chamber and said cylinder, openings in said partition establishing communication between said chamber and said cylinder, an emergency air passage formed in said partition and having an entrance from said chamber intermediate two of said openings, said entrance being controlled by said valve, a yoke-like stop secured to said valve having fingers projecting through said openings into the triple valve cylinder, a spring encircling the stem of said valve and acting to normally close the same and limit the movement of the triple valve piston, and a removable cap nut in the wall of said chamber opposite said partition against which said spring abuts and whereby said valve may be removed from said chamber.
4. In combination with a triple valve and quick-action means for admitting train pipe pressure directly to the brake cylinder, a pressure-reducing valve comprising a casting having a chamber therein, a piston exposed

to air pressure movable in said chamber and normally seated against a shoulder in the upper portion of said chamber, a plurality of annularly arranged radial vents opening into said chamber and adapted to be normally closed by said piston, and a longitudinal radial slot opening into said chamber below said vents and communicating therewith.

5. A pressure-reducing valve comprising a casing containing a chamber, a piston exposed to air pressure movable therein, a seat for said piston and an adjustable spring acting to normally retain said piston upon said seat, a plurality of annularly arranged radial vents in the wall of said casing opening into said chamber and adapted to be normally closed by said piston, a longitudinal radial slot in the wall of said casing spaced from the annular line of said vents and opening into said chamber, and passages in the wall of said casing forming communication between said vents and said slot.

6. A pressure-reducing valve comprising a casing having a chamber therein, a bushing in said chamber, a piston exposed to brake cylinder pressure movable in said bushing, a seat for said piston formed by an inwardly projecting shoulder in the upper part of said bushing, an adjustable spring acting on the piston to normally retain the same upon said seat, a plurality of annularly arranged radial perforations in said bushing adapted to be normally covered by the circumferential face of said piston, a circumferential groove cut in the outer face of said bushing forming a passage adjacent said openings, a longitudinal radial elongated opening in said bushing spaced from the annular line of said perforations and communicating therewith through a groove in the outer face of said bushing, said opening being uncovered when the piston is in its normal position and being adapted to be partially covered when the piston is retracted.

In testimony whereof I affix my signature in the presence of two witnesses.

DAVID S. GILBERT.
